UNITED STATES PATENT OFFICE.

FREDERICK RICHARD SIMMS, OF LONDON, ENGLAND, ASSIGNEE TO THE SIMMS MAGNETO COMPANY, OF BLOOMFIELD, NEW JERSEY, A CORPORATION OF NEW YORK.

MAGNETO-ELECTRIC MACHINE FOR COMBINED IGNITION AND ILLUMINATION PURPOSES.

1,130,206.

Specification of Letters Patent.

Patented Mar. 2, 1915.

Application filed July 14, 1912. Serial No. 773,975.

To all whom it may concern:

Be it known that I, FREDERICK RICHARD SIMMS, a subject of the King of Great Britain, residing at 6 Charles street, 5 Berkeley Square, London, England, have invented new and useful Improvements in Magneto-Electric Machines for Combined Ignition and Illumination Purposes, of which the following is a specification.

10 My invention relates to improvements in magneto-electric machines for generating ignition and illuminating current for use, for example, on motor road vehicles.

Magneto-electric machines of the type 15 above referred to are known wherein two armatures are employed which rotate between two pairs of pole-pieces, one of the said armatures being designed for generating the current for igniting the explosive 20 charge of an internal combustion engine, and the other for generating current designed for supplying the head and other lamps of motor road vehicles.

Now, the object of my present invention 25 is to provide means whereby the leakage of magnetic flux from one pair of pole-pieces is prevented, so that it does not affect the magnetic field of the other pair of pole-pieces, and also, in some cases, to 30 provide means whereby the distribution of the magnetic flux can be adjusted, so that the total flux generated is properly divided between the two magnetic fields.

As hitherto generally constructed magnets and pole-pieces of the kind above referred to have comprised three adjacent magnets, the central magnet being longer than the outside magnets and carrying pole-pieces for the ignition armature, and the 40 other or shorter magnets carrying pole-pieces for the lighting armature. The two pairs of adjacent pole-pieces of each pair were integral with one another or were in close contact, thus providing a free path for 45 the magnetic flux.

Now, according to my present invention I provide a gap, slot or a series of holes or the equivalent in connection with the central magnet carrying the lower pair of 50 pole-pieces, the said gap, slot, holes or the equivalent being located preferably immediately above the upper end of the said lower pole-pieces which are thereby mag-

netically more or less isolated from the pole-pieces. The gap, slot, holes or the like may 55 be disposed in any manner relatively to the magnets; for example, the said gap, slot or the like may be horizontal or at any desired angle to the horizontal.

It will be understood that by proceeding 60 as above described the gap, slot, holes or the equivalent may be varied after the parts have been fitted up or mounted, so that the final adjustment as regards the distribution 65 of the magnetic flux can be made after each machine is complete.

In some cases the adjustment may be effected by cutting away recesses in the pole-pieces or shoe adjacent to the lower ends 70 of the two outside magnets and also cutting a recess between the upper and lower pole-shoes, so as to leave only narrow strips adjacent to each side of the inner or longer magnet. Or, in cases in which the longer inner magnet is not used and the outer magnets 75 are brought slightly lower down the adjustment of the distribution of the flux may be effected by saw-cuts provided in the horizontal plane between the two tunnels in which the armatures rotate. 80

To enable my invention to be fully understood I will describe it by reference to the accompanying drawing, in which:—

Figure 1 is a side view of magneto magnets and pole-pieces constructed according 85 to the invention. Fig. 2 is a section on the line 2—2, Fig. 1. Fig. 3 is a side view of the pole-pieces shown in Fig. 1. Fig. 4 is a view similar to Fig. 3, illustrating a modified construction of pole-pieces, and Figs. 90 5 and 6 are further views illustrating two other variants of the invention. Fig. 7 represents a horizontal section of Figs. 1 and 2 in the horizontal plane of the axis of the upper armature and looking downwardly. 95 Fig. 8 is a horizontal section of Figs. 1 and 2 taken in the horizontal plane of the axis of the lower armature, looking downward.

Referring first to the construction illustrated in Figs. 1, 2, 3, 7, and 8, it will be 100 understood that the magneto illustrated is of the type above specified which comprises three adjacent magnets, *a*, *b*, *c*, each of which comprises three superimposed magnets. The central magnet *b* has its inner 105 portion longer than any of the other mag-

nets, and extending downward through recesses e' in the upper pole shoes e , e , the lower ends of this portion of the magnet b being provided with the lower pole-shoes d , d . The second or intermediate magnet b extends around the upper end of the interior magnet b , and terminates just above the outwardly projecting portions e^2 of the upper pole-shoes. The exterior magnet b surrounds the intermediate magnet but has its outer ends extending downward over the outwardly projecting portions e^2 of the upper pole-shoes. The two inner portions of the magnets a and c terminate at the upper end of the projecting portions e^2 of the upper pole-shoes e and the exterior portions of the magnets a and c have their ends extending downwardly outside of the projecting portions e^2 to the same extent as the exterior magnet portion b . The structure thus arranged is united by means of suitable screws as shown in the drawings. It will thus be seen that the inner magnet b projects below all of the other magnets and carries the lower pole-shoes d , d , which receive the ignition armature d' indicated by dotted lines in Fig. 2; while the outside magnets a and c carry the pole pieces e , e , for the lighting armature e' , also indicated in dotted lines in Fig. 2; the pole shoes d and e are integral on each side of the armatures.

f is the gap, slot or hole which is provided in connection with the central magnet b , this gap or the like being provided immediately above the lower pole-shoe d , that is to say, between the lower pole-shoe d and the upper pole-shoe e , thereby providing a partial magnetic insulation between the said upper and lower pole-shoes.

A magneto-machine made as above described, possesses sundry advantages in practice, chief among which may be mentioned the fact that a machine can be finally adjusted as regards the distribution of the magnetic flux after it has been completely assembled or built up, since the gap, slot, holes or the equivalent may be extended or increased in number after the assemblage—that is to say, should it be desirable to extend the slot after the parts are assembled and the machine tested, the screws which secure the magnets in place with respect to the pole pieces, may be removed so as to allow the magnets to be raised sufficiently to give access to the slot to permit it to be extended more or less as required, without necessitating the entire dismantling of the magneto.

In the modification illustrated in Fig. 4, in addition to the gap, or slot f , there are shown recesses g which are cut in the pole-pieces d adjacent to the lower ends of the two outside magnets a and c so that the said lower pole-shoes are connected to the upper pole-shoes e by strips only.

In Fig. 5, a construction is shown in

which the lower pole-shoes d are entirely separate from the upper pole-shoes e .

Fig. 6 illustrates the application of the invention to magnets of the kind in which the longer magnet b is dispensed with, only the two outer magnets a and c being employed. The said outer magnets a and c are in this case made slightly longer than usual and the distribution of the magnetic flux is controlled by saw-cuts h which are made in the pole-shoes in a horizontal direction between the two tunnels in which the armatures d and e rotate.

Claims:

1. In a magneto electric machine, the combination with magnets, of two pairs of pole-shoes carried thereby, the adjacent members of each pair being integral with each other, said integral pole-shoes being each provided with cutaway portions located substantially between the separate members thereof for securing the partial magnetic insulation of said members from each other.

2. In a magneto electric machine, the combination with a plurality of magnets, a pair of pole-shoes carried by certain of said magnets, a second pair of pole-shoes carried by the other of said magnets and located in a different horizontal plane from the first mentioned pole-shoes, the members of each pair of pole-shoes adjacent to each other being integral and being provided with cutaway portions disposed horizontally and substantially between the members thereof for securing the partial magnetic insulation of said members from each other.

3. In a magneto electric machine, the combination with magnets, of two pairs of pole shoes for the reception of two independent armatures, the individual members of each pair of pole shoes being each integral with the adjacent individual member of the other pair, said integral pole shoes being provided with horizontally disposed slots in a plane between the individual pole shoes for securing the partial magnetic insulation of the individual pole shoe.

4. In a magneto electric machine, the combination with three sets of magnets arranged side by side, a pair of pole-shoes carried by the exterior magnets, the central magnet being provided with portions of greater length than the exterior magnets and extending below the ends thereof, and pole pieces carried by said extending portions of the central magnet, said pole pieces being each integral with one of the pole pieces of the other pair, said integral pole pieces being provided with cutaway portions extending horizontally therein, and located in a plane substantially between the upper and lower pole-shoes.

5. In a magneto electric machine, the combination with a plurality of magnets,

- of two pairs of poleshoes adapted to receive between them separate generating armatures, each member of each pair being connected to a corresponding member of the other pair and said pairs of poleshoes being located one above the other, certain of said magnets being detachably connected to the upper poleshoes and one of said magnets having arms extending below the arms of the first mentioned magnets and being detachably connected to the lower pair of poleshoes, said connected poleshoe members being separated horizontally by cutaway

portions disposed substantially in a plane between the upper and lower members 15 thereof, whereby said magnets having the extended arms may be detached and raised sufficiently to afford access to the poleshoe members for the purpose of enlarging said cutaway portions without effecting the re- 20 lation between the poleshoes and their armatures.
